UNITED STATES PATENT OFFICE

2,448,481

WINDOW SHADE SPRING ADJUSTING
BRACKET

Charles H. Wise, Philadelphia, Pa.

Application August 27, 1946, Serial No. 693,325

1 Claim. (Cl. 160—324)

1

This invention relates to certain new and useful improvements in window shade spring adjusting bracket.

The primary object of the invention is the provision of a simple and inexpensive device adapted for employment for adjustably holding one end of a window shade in position whereby the tension of the spring in the roller may be changed at will for facilitating the raising and lowering of the shade.

A further object of the invention is the provision of a shade roller bracket adapted for permitting the ready adjustment of the spring of the roller without the necessity of removing the roller pintle from the bracket or in any way interfering with the usual shade rolling operation.

With these general objects in view, the invention consists in the novel combination and arrangement of parts hereinafter more fully described in connection with the accompanying drawing and in which like reference characters designate corresponding parts throughout the several views.

In the drawing:

Figure 1 is a front elevation of the invention and the companion bracket with a window shade illustrated by dotted lines in its operative position and broken away;

Figure 2 is an outer end elevational view of the keyed end of the shade roller and bracket with the locking device engaged with the flat pintle of the shade roller;

Figure 3 is an outer end elevational view, similar to Figure 2, with the locking device carried by the bracket disengaged from the flat pintle of the shade roller;

Figure 4 is an inner side view of the bracket supporting the flat pintle of the shade roller with the shade roller pintle shown in section and illustrating the mounting of the locking device on the bracket;

Figure 5 is a cross-sectional view taken on line 5—5 of Figure 2, showing the pivot connection between the shade roller bracket and locking device;

Figure 6 is a cross-sectional view taken on line 6—6 of Figure 2, showing the cam hook carried by the locking device for retaining the latter on the shade bracket;

Figure 7 is a side elevational view of the bracket supporting the flat pintle of the shade roller with the locking device removed; and

Figure 8 is a perspective view of the locking device.

Referring more in detail to the accompanying

drawings, it will be understood that the invention relates to substantially the usual form of window shade 10 adapted for automatic spring winding upon its roller that is journaled at opposite ends in brackets 11 and 12 secured to a window casing as indicated at 13, the bracket 11 being the usual free journaling bracket while the bracket 12 supports the flat pintle of the shade roller that effects winding of the tensioning spring through the medium of the usual ratcheting device associated with the tensioning spring.

This invention having for its primary object the changing of the tension of the winding spring 15 of the shade roller while the latter remains in operative position in both brackets 11 and 12, the invention is primarily concerned with the construction of the bracket 12 and devices associated therewith for engagement with the flat pintle 14 of the shade roller. As shown in detail in Figure 7, the bracket 12 comprises a substantially circular disk head 15 connected by a reduced neck 16 to a mounting plate 17. The disk head 15 is provided with an edge opening 18 inclined slot 18 opening at the upper side of the disk head 15 with the lower end thereof terminating in a circular opening 19 centrally of the disk head 15, the flat pintle 14 of the spring tensioning end of the shade roller being received through the inclined slot 18 for reception in the circular opening 19 as illustrated in Figures 2 to 4.

To retain the end 14 of the tensioning mechanism of the shade roller against rotary movement within the bearing opening 19 therefor, there is provided a locking device carried by the bracket 12 and manually shiftable into and out of engagement with the flat pintle 14. The locking device includes an arcuate plate 20 carrying an angle lug 21 at the outer and upper side thereof and facially projecting from the arcuate plate 20 for pivotal reception in the opening 22 provided in the bracket 12 adjacent its upper edge. To retain the locking device on the bracket 12 there is provided a cam lug extension 23 of inverted U-shape carried by one end of the arcuate plate 20 with the cam lug enclosing the upper edge 15a of the disk head 15 of the bracket 12 and the same end of the arcuate plate 20 that carries the cam 23 is provided with an inwardly extending lug 24 that is shiftable to a position extending over the bearing opening 19 for engagement with the shade roller pintle 14 as illustrated in Figure 2 for retaining the latter against movement. The lock-

ing device comprising the arcuate plate 20 is manually shifted from operative to inoperative positions by means of the leg or finger piece 25 projecting outwardly of the end of the arcuate plate 20 opposite the cam strap 23 and projecting beyond the disk head 15 of the bracket 12 for ready manipulation thereof which will at once be apparent from an inspection of Figures 2 and 3.

To position the shade roller in the brackets 11 and 12, the locking device is shifted to the position shown in Figure 3, with the angle pin or lug 21 pivoting in the opening 22 in the bracket 12 to remove the lug 24 of the locking device from the area of the opening 19. The flat pintle 14 of the shade roller spring device is introduced through the inclined slot 18 and positioned in the circular bearing opening 19, the locking device then being moved on its pivotal lug mounting 21 by engaging the arm 25 to be shifted to the positions shown in Figures 2 and 4, with the lug 24 engaged with the shade roller key 14 as illustrated. This pivotal movement of the locking device causes the cam strap 23 to be frictionally moved into binding engagement with the upper edge 15a of the disk head 15 of the bracket 12 for retaining the locking device in engagement with the shade roller pintle 14. It will be observed from an inspection of Figures 2 and 3, that the reduced connecting neck portion 16 between the bracket mounting plate 17 and the disk head 15 is on an arc to cause the cam lug 23 to be spaced from the edge 15a when the locking device is shifted to its released position as shown in Figure 3. To vary the tension of the spring of the shade roller, the locking device is shifted to the released position shown in Figure 3, whereupon the shade may be wound or unwound from the roller as desired for tensioning the spring of the shade roller, the locking device

being thereafter shifted to locking position with respect to the shade roller flat pintle 14. It will at once be understood that the tension of the shade roller spring may be changed at will while the shade roller remains in its bearings in the two brackets 11 and 12 without removing the shade roller from the bracket as has heretofore been customary.

While there is herein shown and described the preferred embodiment of the invention, it is nevertheless to be understood that minor changes may be made therein without departing from the spirit and scope of the invention as claimed.

I claim:

15 A device of the class described comprising a spring shade roller bracket having an entrance slot and bearing opening adapted for the free journaling reception of the flat pintle of a spring shade roller, a locking device for said pintle comprising an arcuate plate, a lug carried on one edge of the plate for pivotally mounting the plate on the bracket, a lug carried by the plate to be moved over the bearing opening for engagement with said pintle and a strap cam overlying the 20 upper edge of the bracket to be moved into binding engagement with the bracket when the last named lug is engaged with said pintle.
